CLAIM

The ornamental design for a business card display and holder, as shown and described.

DESCRIPTION

FIG. 1 is a front perspective view of a business card display and holder;

FIG. 2 is a top plan view thereof, the bottom plan view being a mirror image thereof;

FIG. 3 is a front elevational view thereof, the rear elevational view being a mirror image thereof;

FIG. 4 is a front perspective view of a business card display and holder in folded position;

FIG. 5 is a top plan view of FIG. 4; and,

FIG. 6 is a right-side elevational view of FIG. 4.
